UNITED STATES PATENT OFFICE.

GEORGE S. SERGEANT, OF GREENSBORO, NORTH CAROLINA.

SAWMILL FEED.

Application filed March 3, 1919. Serial No. 280,344.

To all whom it may concern:

Be it known that I, GEORGE S. SERGEANT, a citizen of the United States, and a resident of Greensboro, in the county of Guilford 5 and State of North Carolina, have invented certain new and useful Improvements in Sawmill Feeds, of which the following is a specification.

My invention relates to improvements in 10 saw mill feeds, and it consists in the constructions, combinations and arrangements herein described and claimed.

The foremost object of the invention is to provide in a saw mill feed mechanism, a 15 novel arrangement in the driving apparatus whereby great flexibility in the application of the feed mechanism to any rackfeed or ropefeed saw mill now in use may be had, regardless of the particular location of the 20 rack or drum shaft, and without regard to the particular dimensions of the husk.

A further object of the invention is to provide a self contained saw mill feed, which can be put on or taken off of any saw mill 25 husk in present use, an additional feature of the saw mill feed being that a perfect driving connection can be gotten to any arbitrarily located drum or rack shaft, this function being directly obtained by means of a 30 novel flexible driving mechanism hereinafter more fully described.

Other objects and advantages will appear in the following specification, reference being had to the accompanying drawings in 35 which:—

Figure 1 is a side elevation of a saw mill feed constructed in accordance with my invention, and illustrating more particularly the improved flexible drive mechanism 40 whereby any arbitrarily located drum or rack shaft can be reached,

Figure 2 is a plan view of the structure shown in Figure 1,

Figure 3 is a longitudinal section taken 45 substantially on the line 3—3 of Figure 2,

Figure 4 is a perspective view of the friction wheel carriage and operating mechanism therefor,

Figure 5 is a perspective view of one of 50 the base angle irons, and

Figure 6 is a detail perspective view of the adjustable box for the idler sprocket wheels.

My present invention is an improvement on 55 the construction of the saw mill feed disclosed in my allowed co-pending application, filed

October 23, 1916, Serial No. 127,156, and as stated in the general objects of the invention, is intended more particularly to enable the universal application of the saw mill 60 feed to any kind of husk, without regard to the dimensions thereof, and without regard to the location of the drum or rack shaft.

A base frame consisting of parallel angle irons 1 and end angle irons 2, provides the 65 foundation on which the drive shaft 3 and the driven shaft 4 are mounted. The mechanism is compactly arranged on the base frame and being self contained, can be applied to any husk 5 now in common use. 70

This feature of universal application of the feed mechanism was also an important feature in the application above referred to, but in addition to this, the arrangement is such in the present instance that the feed 75 mechanism can be applied to any saw mill without making special provision by changing the driving gears, to reach the drum or rack shaft 6.

It can be readily understood that the drum 80 or rack shaft 6 will be invariably located in different places relative to the husk 5 in as many different saw mills. Such being the case, as soon as an attempt is made to gear the saw mill feed up with the drum or rack 85 shaft, it will be found that the gear mechanism must be changed to accommodate the various locations of the shaft 6. There is also always the possibility of a variance in the dimensions of the husk 5, and this also 90 adds to the uncertainty in applying the feed mechanism.

All this uncertainty is overcome in the present invention by using a flexible drive which in the present instance consists of the 95 sprocket chain 7 that runs under the driven sprocket 8 on the shaft 6, over the large drive sprocket 9 on the shaft 4 at the left, and under the small drive sprocket 10 on the shaft 4 at the right. A paper friction drive 100 wheel 11 operates between the driven friction wheels 12 and 13 on the respective shaft 4.

A handle 15 pivoted at 14 at the left end of the base frame, is operated to move the 105 friction drive wheel 11 into contact either with the wheel 12 at the left or the wheel 13 at the right, by means of the boxes 16 in which the drive shaft 3 is eccentrically mounted. These boxes are in turn journaled 110 in large bearings 17 on the base angle irons 1, and have arms 18 to which links 19 are

connected. The links 19 extend to one side where they are connected to arms 20 of a sleeve 21 on the bolt 14 which forms the pivotal mounting previously referred to.

5 As the handle 15 is rocked in one or the other direction, the eccentric boxes 16 are partly turned in the bearings 17, and by carrying the drive shaft 3 to one or the other side of the center, the friction drive 10 wheel 11 is brought into contact with one or the other driven wheels 12, 13. A collar 22 on the inner end of each box 16, provides the means whereby endwise movement of the boxes in the bearings 17 is prevented.

15 It will be apparent at once that the purpose of the double arrangement of the arms 18, 19 and 20 is, to obtain a uniform turning movement and even application of the friction drive wheel 11.

20 The drive shaft 3 carries the drive pulley 23 at the upper end. An idler pulley 24 mounted on the frame 25 which in turn is pivoted on the standard 26 of the base frame, bears on the drive belt 27 which is 25 applied to the pulley 23. An idler sprocket 28 is adjustably mounted on the base frame to take up any slack in the drive chain 7.

Although the provision of the adjustable idler sprocket 28 may appear to be common 30 at first glance, yet in the application of this particular saw mill feed, the ability to adjust the sprocket 28 has an important function. As before stated, the feed mechanism is applicable to any saw mill husk regardless 35 of where the drum or rack shaft 6 is located. In order to apply the invention, it may be necessary to add or take out links of the chain 7, and after doing so, it may be found that the chain hangs looser than 40 it should. It is at this time that the necessity for the idler sprocket 28 arises.

The idler sprocket is journaled in the box 29 which has an extension 30 with a slot 31. The base angle 1 nearest the observer, has a 45 housing 32 in which the extension 30 fits. The cap screw 33 extends through the slot 31 into a hole in the base of the housing, and serves to bind the extension and bearing in place. Vertical adjustments of the

bearing are made by means of the set screw 50 34 which extends up through the bottom.

Attention is directed to Figure 1 wherein a spur pinion 35 is shown in dotted lines on the shaft 6. This showing is intended to indicate that the shaft 6 may either be a 55 rack drive shaft, or the drive shaft of the drum 36 where the saw mill is of the rope drive type. The latter type is now almost universally used, but the invention is applicable to either type equally as well.

60 Each base angle iron 1 is of a special construction as clearly shown in Figure 5. This special construction simply consists of casting the bottom halves 37 of the bearings of the driven shaft 4 and the bottom half 38 of the eccentric bearing, on the base angle iron. This angle iron also includes the housing 32, but since there is but one idler sprocket 28, it follows that the angle iron 65 on the other side does not have a similar housing.

70 While the construction and arrangement of the saw mill drive as herein described and claimed, is that of a generally preferred form, obviously modifications and changes 75 may be made without departing from the spirit of the invention or the scope of the claim.

I claim:—

80 Self-contained feed mechanism for saw mills, comprising a base frame attachable to and removable from a saw mill husk, two normally stationary driven shafts journaled on said frame, each having a friction pulley; a central rotating drive shaft with a friction pulley disposed between the friction pulleys; and means for moving the drive pulley against either friction pulley, comprising eccentric frame-carried boxes for the drive shaft, including collars providing spacers between said boxes and the friction drive pulley, an arm on each eccentric box; a handled sleeve pivoted on the frame with a pair of arms in alignment with the other arms, and connecting links between the respective arms.
